UNITED STATES PATENT OFFICE.

FRIEDRICH DIEDRICH BEHRENS, OF ENON, OHIO.

REIN-HOLDER.

SPECIFICATION forming part of Letters Patent No. 373,716, dated November 22, 1887.

Application filed July 2, 1887. Serial No. 243,297. (No model.)

To all whom it may concern:

Be it known that I, FRIEDRICH DIEDRICH BEHRENS, a citizen of the United States, residing at Enon, in the county of Clark and 5 State of Ohio, have invented a new and useful Improvement in Rein-Holders, of which the following is a specification.

My invention relates to rein holders; and it consists in the construction and arrangement 10 of the parts of the same, which will be more fully hereinafter described, and clearly pointed out in the claim.

In the accompanying drawings, wherein like letters of reference indicate similar parts in 15 the several views, Figure 1 is a perspective view of my improved rein-holder, shown in connection with a portion of the dash-board. Fig. 2 is a rear elevation of my improved rein-holder. Fig. 3 is a top plan view thereof. Fig. 4 is a horizontal section on a line α α of Fig. 2.

A indicates the frame, which is constructed with suitable openings and shoulders for the 20 reception of the parts of the rein-holder.

B represents the clamp-plate, which is 25 adapted to be relatively united or secured to the portion A' of the frame A, the contour of which portion being such as to provide an opening between the two parts when united,

30 which opening is adapted to fit over the welt or bead of the dash-board when the holder is mounted in connection therewith. This clamping-plate B is constructed in the form of a curved plate to conform to the welt or bead of the dash-board, and constructed with 35 upper and lower integral securing-straps, b, having screw-threaded apertures through which the securing-bolts pass. The said plate is adapted to be mounted on the outer portion of the dash-board and clamp the holder and its supporting-frame to the inner side of 40 the said dash-board.

In the frame A two cam-jaws, CC, are mounted, and secured in connection with the frame 45 by means of pintles c', passing through ears c, integrally formed with the cam-jaws C. The upper ends of the jaws C are flared outwardly and formed with smooth surfaces, by means of which construction the reins may be readily 50 inserted between the same, as will be readily understood. The lower ends of the said jaws are formed with integral gear-sections which mesh with each other, and by which motion is imparted from one jaw to the

other. These gear-sections c² are slightly circular, and are adapted to make the motion of the two jaws uniform. The inner opposing faces of the said jaws are formed with corrugations c³, which bite upon the lines or reins when inserted between said jaws and prevent 55 the same from becoming disengaged therefrom. The ears c, formed integrally with the under jaw, C, bear against the outer side of the frame A, and form a stop to limit the movement of the said jaw, and, through the medium of the meshing gear-sections, of the cooperative movement of both jaws.

A coil-spring, S, surrounds the pintle c', passing through the ears c, which bear against the side of the frame, as just described, the 70 said spring being situated between the said ears, the one arm, s, thereof bearing upon the frame A, and the other arm, s', thereof engaging with one of the ears of the jaw in connection with which it is mounted. By this means the 75 said jaws C are returned to a closed position, as shown in Fig. 1, and also caused by said construction to provide a more positive securement between the jaws and the reins.

The manner of applying my improved holder 80 in connection with the dash-board will be readily understood, suitable screws being used to unite the clamping parts.

The novelty and utility of my improved device being obviously apparent and appreciable, it is unnecessary to further enlarge upon the same herein.

Having thus described my invention, what I claim as new is—

The improved rein-holder herein described 90 and shown, comprising the frame A, having the clamping portion A', and the clamp B, acting with said clamping portion, the jaws C, pivotally mounted in said frame A and having the lower meshing portions, c², the opposing faces of the jaws having the lower corrugated portions and the smooth outwardly-turned upper ends, and a spring, S, acting upon the said jaws to hold them normally together, substantially as specified.

In testimony that I claim the foregoing as my own I have hereto affixed my signature in presence of two witnesses.

FRIEDRICH DIEDRICH BEHRENS.

Witnesses:

FRANK LAYTON,
EDWARD BAKER.
